UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

HAMMER-DRILL.

1,242,882.

Specification of Letters Patent.

Patented Oct. 9, 1917.

Application filed March 2, 1915. Serial No. 11,561.

To all whom it may concern:

Be it known that I, GEORGE H. GILMAN, a citizen of the United States, and a resident of Claremont, county of Sullivan, and 5 State of New Hampshire, have invented an Improvement in Hammer-Drills, of which the following description, in connection with the accompanying drawings, is a specification, like characters on the drawings representing like parts.

This invention relates to hammer drills and more particularly to hammer drills of the self-rotating type. The object is to provide means to prevent the entrance of dirt 15 or grit into the chuck bearing and the internal working parts of a self-rotating hammer drill when it is used for drilling vertical or approximately vertical holes.

The invention will be best understood 20 from the following description when taken in connection with the accompanying illustration of one specific embodiment thereof, while its scope will be more particularly pointed out in the appended claims.

25 In the drawings:—

Figure 1 is a side elevation of a pressure fed stoping hammer drill embodying one form of the invention; and

30 Fig. 2 is a sectional elevation showing, on an enlarged scale, the construction of the front head of such drill.

Referring to the drawings and to the embodiment of the invention therein shown, the stoping tool is of the percussive hammer 35 drill type, provided with a cylinder 1, secured to the head block 2, the latter connected to the pneumatic feed cylinder 3. The feed cylinder is provided with a feed piston 4, connected to the piston rod 5, provided with a projecting pointed end 6, whereby, as is common with devices of this 40 class, the tool, after being set in position, may be fed toward its work by the admission of pressure fluid from a suitable source (not shown) to the feed cylinder 3. The latter is under the control of a main controlling valve, the handle for which is shown at 7, such controlling valve serving also to control the throttle for the tool. The cylinder 1 is provided with a cylinder head 8 and overlaps the front head 10, and the front head, cylinder, head block and feed cylinder are all securely clamped together by means of the side rods 11, passing rearwardly 45 through flanges 12 in the front head and

secured at their opposite ends to a yoke 13, the latter being seated upon the front end of the feed cylinder at the rear of the head block.

Referring now to the construction of the 60 front head and the parts connected therewith for rotating the drill steel, the chuck for receiving the latter is rotatably mounted in the front head 10, and has a forward portion 14 projecting from the front head. 65 Such a forward portion has a bore adapted to receive the drill-receiving bushing 15, and is split along the line 16 whereby the bushing 15, after insertion, may be clamped tightly in position by means of the clamping bolt 17 carried by the lugs 18 formed on the projecting portion 14 of the chuck. The bushing 15 has a bore preferably of a 70 hexagonal or other non-circular cross section suitable to receive the end of the drill bit 75 and hold the same non-rotatable in the chuck.

The drill steel (indicated in dotted lines in Fig. 2) when inserted in the chuck is seated against the front face of a tappet or 80 anvil block 20, the latter consisting of a portion of larger diameter arranged in the larger bore of the chuck member, and a shank 21 of smaller diameter projecting rearwardly through a chuck of smaller bore 85 diameter, whereby there is provided a shoulder 22 on the block seated against a shoulder in the chuck and whereby the smaller portion of the anvil block projects back into the path of the piston hammer extension 90 23, and is adapted to receive the impact thereof and transmit the same to the drill steel.

The hammer extension 23 is rigidly secured to and projects forwardly from the 95 piston hammer 24 through a bore in the cylinder head 8. The piston is arranged to reciprocate in the cylinder 1 as is usual in this class of devices, and any usual or ordinary controlling valve (not shown) may be 100 used.

The portion of the chuck which is rotatably mounted within the cylinder head includes the rearward anvil-carrying portion 25, the rear end of which bears against the 105 front face of the shouldered portion 26 in the front head, and a rearward extension 27, the latter in the form of a chuck sleeve secured to the chuck portion 25 by any suitable means as by threaded engagement 110

therewith, and having an internal bore of suitable diameter to slidably fit the hammer extension 23. The rearward extension 27, or sleeve, is provided with a flange or enlarged shoulder 28, the forward face of which abuts against and engages with the rearward face of the shoulder 26 on the front head. By this means, the chuck is not only rotatably mounted within the front head, but is retained therein, and its longitudinal displacement prevented.

To rotate the chuck suitable means are provided for turning the piston and the hammer extension step-by-step, such rotative step-by-step movement being communicated to the chuck by means of the keys 29 fixed in the rearward extension 27 of the chuck, said keys being slidably engaged by straight grooves 30 in the hammer bar extension.

Any suitable means may be employed for imparting a step-by-step rotative movement to the piston, but herein I have shown devices which are substantially the same as those shown in my prior Patent No. 1,034,010, to which reference may be had for fuller details. Such rotative mechanism embodies a ratchet member 31 having interior helical keys or teeth (not shown) slidably engaged with helical grooves 32 formed in the piston extension, said ratchet being freely rotatable in one direction, but locked against movement in the opposite direction by suitable clutching devices, herein shown in the form of rollers 33, engaging the teeth of the ratchet and pressed against the same by the springs 34.

In order to prevent the entrance of dust or grit into the bearing parts of the chuck or the internal working parts of the drill, the forward or projecting portion 14 thereof is provided with means which overlap and protect the joint between the front head and the chuck. While such protection might be embodied in the form of a separate attachment, herein it is provided by enlarging the diameter of the projecting portion 14 so that the latter is in the form of a nose-piece provided with a flange 35 overlapping the forward end of the front head and protecting the joint thereat from the entrance of dust or grit. Preferably passages 36 are provided which extend at an inclination rearwardly from the chuck projecting portion 14 so as to connect the space at the front of the anvil block with the open air and thereby permit the escape of any dust or grit which accumulates in or enters the said space.

While I have herein shown and described for purposes of illustration one specific form of my invention, it is to be understood that extensive deviations may be made from the construction herein disclosed without departing from the spirit of the invention, and

that not only is the same capable of embodiment in a great variety of forms, but that it may be applied to tools of widely different construction from that herein shown.

Claims:

1. In a fluid operated percussive drill, a cylinder having a flange on its front end, a front head seated within said flange, and a two-part rotatable drill chuck seated in said head and interlocked therewith having a portion overlapping the front end thereof.

2. In a fluid operated percussive drill, a cylinder having a flange on its forward end, a front head seated in said flange and overlapped thereby, a two-part rotatable drill chuck seated in said head and having a portion overlapping the front end thereof and a portion threaded thereto co-operating therewith in interlocking said head and chuck against longitudinal movement.

3. In a fluid operated percussive drill, a cylinder, a front head seated therein having an internal annular flange at a point intermediate its ends, and a two part drill chuck seated in said head having a portion overlapping the front end of said head and a co-operating flanged portion engaging the rear wall of the flange on said head.

4. In a fluid operated percussive drill, a cylinder, a front head seated thereon having an internal annular flange, and a drill chuck seated in said head comprising a pair of connected sections, one having a portion engaging the front wall of said flange and the other having a flange portion engaging the rear wall of the flange on said front head.

5. In a fluid operated percussive drill, a cylinder, a front head seated thereon having an internal annular flange, and a drill chuck seated in said head comprising a plurality of sections threaded together at their opposite ends and one having a portion engaging the front wall of said flange and the other having a flange engaging the rear wall of said flange.

6. In a fluid operated percussive drill, a cylinder, a front head seated on said cylinder, said front head having an internal projection thereon, a drill chuck disposed within said head and having its rear wall in engagement with the front wall of said projection, and a co-operating drill chuck member removably attached to said chuck having a flange thereon engageable with the rear wall of said projection.

7. In a fluid operated percussive drill, a cylinder, a cylinder head therein, a piston movable through said head, rotative mechanism in said cylinder beyond the front end of said head, a front head in said cylinder having an internal annular flange, a flanged chuck member engaging the rear wall of said flange and co-operating with said cylinder head to confine said rotative mechanism,

and a coöperating chuck member threaded thereto having a portion engageable with the opposite wall of said flange.

8. In a fluid operated percussive drill, a cylinder, a front head seated in the front end thereof and overlapped thereby having an internal annular flange intermediate its ends, a drill chuck member rotatably mounted in said head having its rear end of increased internal diameter and extending to a point adjacent the front wall of said flange, and a coöperating chuck member threaded within the rear end of said first mentioned member and having an annular flange on its rear end engaging the rear wall of the flange on said front head.

9. In a fluid operated percussive drill, a cylinder, a cylinder head therein, a piston having a reduced end movable through said head, rotative mechanism in said cylinder in front of the front end of said head and operatively connected to said piston, a front head seated in the front end of said cylinder, and a drill chuck operatively connected to said piston interlocked with said front head against longitudinal movement and coöperating with the latter to confine said rotative mechanism.

10. In a fluid operated percussive drill, a cylinder, a cylinder head therein, a front head seated in said cylinder, a piston having a fluted hammer extension movable through said cylinder head, rotative mecha-

nism including a ratchet coöperating with said fluted extension and disposed between 35 said cylinder head and front head, an internally fluted chuck member seated in said front head and coöperating with said cylinder head to confine said ratchet, and a chuck member coöperating therewith in locking 40 said chuck against longitudinal movement.

11. In a fluid operated percussive drill, a cylinder, a cylinder head therein, a front head seated in said cylinder and overlapped thereby, having an internal flange thereon, 45 a piston having a fluted hammer extension movable through said cylinder head, rotative mechanism including a ratchet coöperating with said fluted extension and disposed adjacent said cylinder head, an internally fluted chuck member seated in said front head and having a flange engaging the flange thereon and coöperating with said cylinder head to confine said ratchet, and a coöperating chuck member attached to said 55 chuck member and likewise engaging the flange on said front head having an enlarged front portion overlapping the forward end of said front head.

In testimony whereof, I have signed my 60 name to this specification, in the presence of two subscribing witnesses.

GEORGE H. GILMAN.
